AUTOMATIC TELEPHONE SYSTEM.

1,315,445.

Specification of Letters Patent.

Patented Sept. 9, 1919.

Application filed May 31, 1917. Serial No. 171,815.

To all whom it may concern:

Be it known that I, TALBOT G. MARTIN, a citizen of the United States of America, and a resident of Chicago, county of Cook, 5 and State of Illinois, have invented certain new and useful Improvements in Automatic Telephone Systems, of which the following is a specification.

My invention relates in general to automatic telephone systems, but more particularly to such systems as comprise a plurality of exchanges interconnected by trunk lines; and the object of the invention is to provide an improved repeater for use in the inter-office trunk circuits, whereby the quality of 10 telephonic transmission for a certain class of calls, hitherto below the standard, is improved greatly and is made substantially equal to the average quality of transmission 15 in the system.

The above indicates in general terms the purpose and scope of the invention. The manner in which the same is to be used, its mode of operation, and the advantages derived from its incorporation in a telephone 20 trunking system of the character described, will all be fully explained hereinafter, reference being had to the accompanying drawings.

In the drawings Figure 1 is a schematic diagram illustrating the general layout of a portion of a system which is well adapted for the use of my improved repeater, while Fig. 2 is a complete circuit diagram of two 30 selector switches and a repeater, wired in accordance with the invention, which are shown only symbolically in Fig. 1.

Referring to the layout Fig. 1, I have shown at the right of the dotted line certain apparatus in one of the main exchanges of the system, while to the left is shown a branch exchange subsidiary to the main exchange. The main exchange may be a five digit system, and local connections will then 40 be established through the medium of individual line switches, first, second, and third selector switches, and connector switches. For example, the subscriber at substation A 45 may establish connection with the subscriber at substation A' by means of the individual line switch C, the first selector E, the second

selector F, the third selector H, and the connector I. This is the usual and well known percentage trunking system and needs no detailed explanation.

The branch exchange may be a three digit system comprising individual line switches, first selectors and connectors. A calling subscriber at substation A² may extend a connection to the substation A³ by means of 55 line switch C', the first selector E², and the connector I'. Subscribers in the branch exchange of course can also call subscribers in the main exchange, and for this purpose a certain bank level (assuming that the Strowger type switches are used) of the first selectors, such as the selector E², is reserved for trunk lines extending to the main exchange. Thus the selector E² not only has access to a plurality of groups of connectors, 60 such as the group which includes the connector I', but also has access to a group of trunk lines extending to the main exchange and terminating there in first selector switches, termed incoming selectors. One of 65 these trunk lines is the trunk line 2 which extends by way of the repeater R' to the main exchange and terminates in the incoming selector E'. The incoming selectors have access to second selectors of the local 70 trunking system in the main exchange and their banks therefore are multiplied with the banks of certain local first selectors such as the selector E. For the purpose of giving main exchange subscribers access to lines in 75 the branch exchange, a certain bank level of a group of third selectors may be assigned to trunk lines extending from the main to the branch exchange. One of these trunk lines is shown extending from the bank of 80 third selector H by way of repeater R² to the branch exchange where it terminates in the selector E³.

The other main exchanges of the system, 85 of which there may be one or more, are preferably each accessible to subscribers in the main exchange shown from a particular first selector level. Thus a certain level of the selectors E and E' may be assigned to a group of trunk lines extending to a second 90 main exchange and terminating there in second selectors. One of these trunk lines is 95 100

the trunk line 3 which extends by way of the repeater R to a second selector (not shown) in the second main exchange. It will be seen now that the main exchange subscriber 5 at substation A can extend a connection to the second main exchange by way of line switch C, first selector E, repeater R, and trunk line 3; while the branch subscriber at substation A² can extend a connection to the 10 same point by way of line switch C', first selector E², repeater R', trunk line 2, incoming selector E', repeater R, and trunk line 3.

From the foregoing brief description of a typical trunking system the purpose and 15 utility of my invention may easily be understood. When the subscriber at substation A extends a connection over the trunk line 3 his transmitter is supplied with talking current from the front bridge or controlling 20 relay of the repeater R, which must be of sufficiently low resistance to permit the flow of the requisite amount of talking current. But when the branch subscriber at substation A² extends a connection over trunk line 25 3 transmitter current is supplied from the front bridge of repeater R', and thus it will be seen that in this latter case it is extremely desirable that the front bridge in repeater R be of high resistance, or there 30 will be excessive transmission loss. By my invention the repeater R is so designed that when it is seized by a local first selector such as the selector E the usual front bridge will remain across the talking circuit during 35 conversation for the purpose of supplying transmitter current to the calling line in the customary manner; but when it is seized by an incoming selector such as selector E', when the called subscriber answers an additional coil of high resistance and impedance 40 is inserted in the bridge, thereby greatly reducing the transmission loss.

The manner in which this is accomplished can best be explained by describing briefly 45 the operation of the incoming selector E' and the repeater R during the establishment of a connection, and such description will now be proceeded with, reference being had to Fig. 2. First, however, certain publications will be cited as illustrating well known 50 features of the equipment involved, in order to avoid the necessity of too elaborate an explanation. The mechanical construction of the switches is shown in U. S. Letters Patent 55 Nos. 815,321, and 815,176, both granted March 13, 1906, to Keith, Erickson, and Erickson. Circuits of a modern two wire 60 automatic system are shown in U. S. Patent No. 13,901, reissued April 13, 1915, to Frank Newforth. A repeater having the general 65 functions of the ones herein shown is disclosed in U. S. Patent to Martin, No. 1,136,912, granted April 20, 1915.

To proceed with the operation, when the 70 subscriber at substation A² removes his re-

70 cover to initiate the call, the line switch C' is operated in the usual manner to extend the line of substation A² to an idle first selector switch, which we may assume to be the selector E². The calling device at substation A² is now operated in accordance with the first digit of the desired number, resulting in the operation of selector E², whereby an idle trunk line extending to the main exchange is selected and connection established therewith. Assuming that the selected trunk line is the trunk line 2, when it is seized by the selector E², the front bridge or controlling relay of the repeater 75 R' is energized over the calling subscriber's 80 loop; and as a result of the energization of this controlling relay a bridge is closed across the conductors of the trunk line extending between the repeater R' and the selector E' at the main exchange. The line 85 relay 10 of the selector E' is accordingly energized and upon attracting its armature closes a circuit for the slow acting release relay 11. Upon energizing in turn, relay 11 prepares circuits for the vertical and 90 rotary magnets 14 and 15 in the well known manner.

The calling subscriber may now operate his calling device in accordance with the second digit of the desired number, thereby 95 producing a series of interruptions or impulses in the circuit of the controlling relay of the repeater R'. These interruptions are repeated in the usual way into the circuit of the line relay 10 of the selector E' in the 100 main exchange. It follows that the line relay 10 is deenergized a corresponding number of times, and at each deenergization an impulse from ground G¹ is transmitted through the slow acting relay 12 and the 105 vertical magnet 14 in series. The vertical magnet in response to these impulses operates to step up the switch shaft until the wipers 40, 41 and 42 arrive at the horizontal level 110 of bank contacts which constitute terminals of the trunk lines extending to the second main exchange.

The relay 12 is energized in series with the vertical magnet, and being slow acting, retains its armature during the series of impulses. Upon the first upward movement of the shaft the off normal springs 18 are closed, thereby completing an initial energizing circuit for the stepping relay 13 which may be traced as follows: ground at 115 120 (1²), working contact of armature 21 and the said armature, armature 22 and its working contact, off normal springs 18, and the winding of relay 13 to battery. Upon energizing, relay 13 locks itself to ground G² at its 125 upper armature 23 and at its lower armature 24 prepares a circuit for the rotary magnet 15 which is held open, however, during the vertical movement of the switch by the slow 130 acting relay 12. At this point it should be

mentioned that by the closure of off normal springs 18 the line switching relay 16 and the stepping relay 13 were connected in series. But since the junction of the two 5 relays has already been connected to ground as described, relay 16 is short circuited and remains inoperative for the present.

When the slow acting relay 12 deenergizes at the end of the series of impulses it 10 completes at the back contact of its armature 22 the circuit of the rotary magnet 15 extending as follows: ground at G^a , working contact of armature 21 and the said armature, armature 22 and its resting contact, 15 armature 24 and its working contact, and the winding of the rotary magnet 15 to battery. Upon energizing, the rotary magnet operates to rotate the wipers 40, 41 and 42 into engagement with the first set of bank 20 contacts in the level opposite which they were raised. Near the end of its stroke the rotary magnet opens its interrupter contact, thereby breaking the locking circuit of the stepping relay 13. Upon deenergizing, relay 13 breaks the energizing circuit of the 25 rotary magnet which accordingly retracts its armature to again close its interrupter contact. The operation now depends upon whether or not the first trunk line, the terminals of which are now engaged by the selector wipers, is busy or not. If this trunk 30 line is busy there will be a ground potential upon the test contact with which the private wiper 41 is in engagement, and this ground potential will serve to maintain 35 the switching relay 16 short circuited and to again energize the stepping relay 13. The rotary magnet circuit is therefore again completed and the foregoing operations are 40 repeated, whereby the selector wipers are advanced into engagement with the next set of contacts. It will be seen then that the stepping relay 13 will operate to advance the switch wipers step by step through the 45 medium of the rotary magnet as long as the private wiper 41 continues to engage grounded or busy test contacts. When an idle or non grounded test contact is reached, assumed to be the test contact 44, and the rotary magnet retracts its armature, the 50 switching relay 16 will no longer be short circuited but will instantly energize in series with the relay 13. Owing to the high resistance of relay 16 relay 13 remains inoperative. Upon energizing, relay 16 opens at 55 its armature 25 a contact in the circuit of the release magnet 27 to guard against the release of the switch upon the deenergization of relays 10 and 11; shifts the private wiper 60 41 from connection with its upper terminal into connection with its lower terminal at armature 29; and at armatures 28 and 26 disconnects the conductors of the trunk line 2 from the windings of the line relay 10 and 65 extends them by way of wipers 40 and 42,

bank contacts 43 and 45, conductors 46 and 48, and normally closed contacts of the reversing relay 106 to the windings of the double wound line relay 100 of the repeater R.

Upon energizing, the line relay 100 closes the usual circuit for the slow acting release relay 101. The relay 101, upon energizing, completes a holding circuit for the selector E' as follows: ground at G^a , working contact of armature 111 and the said armature, winding of relay 105, conductor 47, bank contact 44, private wiper 41, armature 29 and its working contact, winding of relay 16, interrupter contact of the rotary magnet 15, 70 off normal springs 18, and the winding of the stepping relay 13 to battery. It is to be understood that this circuit is established before the release relay 11 has had time to deenergize. The relay 105 of the repeater which is included in the holding circuit is of low resistance so that the test contact 44 and its multiples in the banks of the other incoming selectors are brought sufficiently near to ground potential to make the 80 trunk line busy. This ground potential also extends over conductor 50 to multiple test contacts in the banks of the local selectors such as the selector E where the trunk line 3 is made busy also. It will be observed 85 that a branch of the above described holding circuit extends through the coil 17 at the selector E' to battery. This multiple path permits sufficient current to flow through the winding of relay 105 at the repeater to 90 energize it, with results which will be described later.

Proceeding now with the operations at the repeater R resulting from the energization of the relay 101, at its armature 112 105 this relay prepares a circuit for the slow acting relay 102 and at its armature 111 closes a circuit through the polarizing winding of relay 103 as follows: ground at G^a , working contacts of armature 111, and the 110 lower winding of the said relay 103. The lower winding of relay 103 is of high resistance and few turns, being composed in part of German silver wire, and relay 103 is therefore not sufficiently energized to attract its armatures. A still further result of the energization of relay 101 is the closure of a bridge across the conductor of the trunk line 3 extending to the second main exchange 115 which may be traced as follows: upper conductors of trunk line 3, armature 110 and its working contact, armature 113 and its resting contact, upper winding of relay 103, spring 119, contact 120, right hand winding of impedance coil 107, armature 121 of the 120 line relay 100 and its working contact, to the lower conductor of trunk line 3. By the closure of this bridge the line relay of the second selector at the distant main exchange 125 is energized with results similar to those 130

which were described in the case of the line relay 10 of the selector E'. Although the upper winding of relay 103, which is included in the bridge as traced, is connected in series with the line relay of the distant second selector, the relay 103 is not operationally energized for its windings are so connected that their energizing effects at this time are in opposition.

10 The calling subscriber may now operate his calling device in accordance with the third digit of the desired number, thereby producing another series of interruptions in the circuit of the controlling relay of repeater R', which interruptions are now repeated into the circuit of the relay 100 of the repeater R. The line relay 100 is accordingly deenergized a number of times corresponding to the number of interruptions produced in its circuit and at each deenergization transmits an impulse to the slow acting relay 102 over the following path: ground at G³, armature 122 and its resting contact, armature 112 and its working contact, and the winding of slow acting relay 102 to battery. The slow acting relay 102 remains energized continuously during the intermittent deenergization of line relay 100 and completes the bridge 25 across the conductors of the trunk line 3 over a new path, exclusive of inductive windings, which may be traced as follows: upper conductor of trunk line 3, armature 110 and its working contact, armature 113 30 and its working contact, and the armature 121 of the line relay 100 and its working contact, to the lower conductor of trunk line 3. While this new bridge excludes the upper winding of relay 103 and the right hand 35 winding of the impedance coil 107 it will be seen that it still includes the armature 121 of the line relay 100, and it follows therefore that at each deenergization of the line relay an interruption will be produced 40 in the circuit of the line relay of the second selector at the distant main exchange. This second selector is accordingly operated in the usual manner to establish connection with a trunk line extending to an idle third selector. At the end of the series of interruptions the slow acting relay 102 deenergizes and the bridge across the trunk line 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760

The calling subscriber may now operate his calling device for the remaining digits in the called number with the result that the selected third selector and a connector switch are operated to complete the connection to the desired called line. After the connection is completed the called subscriber may be signaled in the customary manner by means of automatic equipment associated with the connector switch. When the called subscriber answers the signaling operation 65 is stopped and a relay in the connector,

which may be the usual answering bridge, is energized over the called subscriber's line to reverse the direction of current flow over the conductors of the trunk line 3. As a result of this operation the direction of current flow in the upper winding of relay 103 is reversed and since now the two windings of this relay assist each other it will at once energize. By the attraction of armatures 114 and 115 the heavy talking conductors of the repeater are extended through to the conductors of the trunk line 3 independent of contacts of relays 100 and 102; and by the attraction of armature 116 a circuit is completed in an obvious manner 70 for the reversing relay 106. Relay 106 is accordingly energized and at its armature 126 connects the left hand winding of impedance coil 107 in series in the bridge across the trunk line 3. The left hand winding 85 of impedance coil 107 is of high resistance and impedance for the purpose of reducing as far as possible transmission loss due to this bridge. As a further result of its energization relay 106 reverses the conductors 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760

When the subscriber at substation A extends a connection to the second main exchange by way of the trunk line 3 the operations are as follows: Upon the removal of the receiver the line switch C 130

operates to extend the calling line to a first selector switch, which we will assume to be the selector E. The line relay 150 of the selector E is accordingly energized over the conductors 152 and 163 to which the calling line has been extended by the operation of the line switch and closes the usual energizing circuit for the slow acting release relay 151. The relay 151, upon energizing, 5 connects ground to the conductor 144 in order to maintain the line switch in operated position. By the operation of the calling subscriber's calling device the selector E is now operated similar to the manner in which the selector E' was operated to select 10 an idle trunk line extending to the second main exchange, and we will assume in this case also that the trunk line 3 is the one selected. Upon the seizure of the trunk line 15 3 the line relay 100 and release relay 101 are energized, the latter relay serving to complete a holding circuit for the selector E which as in the previous case includes the winding of relay 105. It will be observed, 20 however, that the selector E has no coil corresponding to the coil 17 of the selector E', and it follows therefore that when the holding circuit for selector E is completed the current flow through the winding of relay 25 105 will be insufficient to enable it to energize. In other words, relay 105 is a marginal relay which will energize only when the repeater R is seized by a selector switch which is provided with a coil 17. 30 Needless to say all selectors similar to the selector E' are provided with such resistance coils while the selectors such as the selector E are not so provided. 35

The apparatus in the distant main exchange 40 is now controlled through the medium of the repeater R in the manner previously described until the connection is finally established with the line of the called subscriber. When the receiver is 45 removed at the called substation the relays 103 and 106 of the repeater are energized as before and with the same results with one exception, however. Since the relay 105 in this case is deenergized the operation of 50 relay 106 serves merely to reverse the conductors 49 and 51 as regards their connections to the windings of line relay 100 and does not operate to include the windings of the impedance coil 104 in these connections. 55 This is true because when the relay 105 is deenergized its armatures 117 and 118 short circuit the windings of relay 104 at their resting contacts. It will be seen then that the line relay 100 of the repeater alone is 60 left in bridge of the conductors 49 and 51 during conversation, thereby affording an ample supply of transmitter current to the calling substation. The reversal of current flow in the calling line produced by the 65 energization of relay 106 may be used to

cause the actuation of a meter or coin collecting device in any well known or desired manner.

Having described my invention what I consider to be new and desire to have protected by Letters Patent will be pointed out in the appended claims. 70

What I claim as my invention is:

1. In a telephone system, two subscribers' lines, means including a repeater for setting up a circuit connection from either of said lines to a called line for talking purposes, a controlling relay bridge across said circuit in said repeater, and means in said repeater effective to increase the impedance 75 of said bridge during conversation only when a particular one of said first lines is included in the connection. 80

2. In a telephone system, two subscribers' lines, means including a repeater for setting up a circuit connection from either of said lines to a called line for talking purposes, a controlling relay bridge across said circuit in said repeater, and means comprising 85 a marginal relay in said repeater effective 90 to increase the impedance of said bridge during conversation only when a particular one of said first lines is included in the connection. 95

3. In a telephone system, two subscribers' lines, means including a repeater for setting up a circuit connection from either of said lines to a called line for talking purposes, a controlling relay bridge across said circuit in said repeater, and means in said repeater 100 effective to increase the resistance of said bridge during conversation only when a particular one of said first lines is included in the connection. 105

4. In a telephone system, a trunk line including a repeater, means for setting up a circuit connection over said trunk line from two different points for talking purposes, a controlling relay bridge across said circuit in said repeater, an impedance coil for insertion in the bridge, and discriminating means in said repeater effective to cause the inclusion of said coil in the said relay bridge only when a connection is extended over said 110 trunk line from a particular point. 115

5. In a telephone system, a trunk line including a repeater, means for setting up a circuit connection over said trunk line from two different points for talking purposes, a controlling relay bridge across said circuit 120 in said repeater, an impedance coil, and discriminating means comprising a marginal relay in said repeater effective to cause the inclusion of said coil in the said relay bridge only when a connection is extended over said 125 trunk line from a particular point. 130

6. In a telephone system, two subscribers' lines, means including an electromagnetic switching mechanism for setting up a circuit connection from either of said lines to a

- called line for talking purposes, a battery supply bridge across said circuit included in said mechanism for supplying talking current to a calling line, means for supplying 5 one of said first lines when calling with talking current from a different point, and automatic means for increasing the resistance of said bridge when the connection is extended from the calling line last mentioned.
- 10 7. In a telephone system, first and second subscribers' lines, means including a switching mechanism controllable over either of said lines when calling for extending a talking connection to a called line, a battery supply 15 bridge in said mechanism, and discriminating means for increasing the impedance of said bridge if a particular one of said first lines is included in the connection.
8. In a telephone system, first and second subscribers' lines, means including an electromagnetic switching mechanism controllable over either of said lines when calling for extending a talking connection to a called line, a battery supply bridge in said 20 mechanism, means for supplying talking current by way of said bridge to the said first line after the connection is completed, and means whereby if the said second line is the calling line the resistance and impedance 25 of said bridge is automatically increased.
9. In a telephone system, first and second subscribers' lines, means including an electromagnetic switching mechanism controllable over either of said lines when calling 30 for extending a talking connection to a called line, a battery supply bridge in said mechanism, and discriminating means for changing the resistance of said bridge if a particular one of said first lines is included 35 in the connection.
- 40 10. In a telephone system, selector switches of two different kinds, a repeater accessible to said switches, means including either one of said switches and said repeater for connecting calling and called lines, a battery supply bridge in said repeater, and discriminating means whereby if an established connection includes a selector switch of particular kind the impedance of said bridge is increased.
11. In a telephone system, selector switches of two different kinds, a repeater accessible to said switches, means including either one of said switches and said repeater for connecting calling and called lines, a battery supply bridge in said repeater, and discriminating means whereby if an established connection includes a selector switch of particular kind the resistance of said bridge is altered.
- 55 12. In a telephone system, selector switches of two different kinds, a repeater accessible to said switches, means including either one of said switches and said repeater for connecting calling and called lines, a battery supply bridge in said repeater, and discriminating means whereby if an established connection includes the other of said selector switches the impedance of said bridge is increased.
- 60 13. In a telephone system, selector switches of two different kinds, a repeater accessible to said switches, means including either one of said switches and said repeater for connecting calling and called lines, a battery supply bridge in said repeater, and discriminating means whereby if an established connection includes a selector switch of particular kind the impedance of said bridge is increased, the said means comprising a marginal relay in said repeater, a conductor including a winding of said relay adapted for seizure by said switches, means in the switches of one kind for causing a certain current flow in said conductor, and means in the switches of the other kind for causing a different current flow in said conductor.
- 65 14. In a telephone system, a trunk line consisting of talking conductors accessible from two different points, means for extending a connection from either point over said trunk line to a called telephone line, a battery supply bridge connected across the talking conductors of said trunk line, and automatic means effective only when a connection is extended over said trunk line from a particular point for increasing the impedance of said bridge.
- 70 15. In a telephone system, a trunk line consisting of talking conductors accessible from two different points, means for extending a connection from either point over said trunk line to a called telephone line, a battery supply bridge connected across the talking conductors of said trunk line, and automatic means effective only when a connection is extended over said trunk line from a particular point for altering the resistance of said bridge.
- 75 16. In a telephone system, two selector switches, a repeater accessible to said switches, means including either one of said switches and said repeater for connecting calling and called lines in a talking circuit, a controlling relay bridge in said repeater, whereby if an established connection includes one of said selector switches talking current is supplied to the talking circuit via said last mentioned selector, and means whereby if an established connection includes the other of said selector switches the impedance of said bridge is increased.
- 80 17. In a telephone system, a trunk line consisting of talking conductors accessible from two different points, means for extending a connection from either point over said trunk line to a called telephone line, a battery supply bridge connected across the talking conductors of said trunk line, and automatic means effective only when a connection is extended over said trunk line from a particular point for causing a certain current flow in said conductor, and means in the switches of the other kind for causing a different current flow in said conductor.
- 85 18. In a telephone system, selector switches of two different kinds, a repeater accessible to said switches, means including either one of said switches and said repeater for connecting calling and called lines, a battery supply bridge in said repeater, and discriminating means whereby if an established connection includes a selector switch of particular kind the resistance of said bridge is altered, the said means comprising a marginal relay in said repeater, a conductor including a winding of said relay adapted for seizure by said switches, means in the switches of one kind for causing a certain current flow in said conductor, and means in the switches of the other kind for causing a different current flow in said conductor.
- 90 19. In a telephone system, a trunk line consisting of talking conductors accessible from two different points, means for extending a connection from either point over said trunk line to a called telephone line, a battery supply bridge connected across the talking conductors of said trunk line, and automatic means effective only when a connection is extended over said trunk line from a particular point for causing a certain current flow in said conductor, and means in the switches of the other kind for causing a different current flow in said conductor.
- 95 20. In a telephone system, a trunk line consisting of talking conductors accessible from two different points, means for extending a connection from either point over said trunk line to a called telephone line, a battery supply bridge connected across the talking conductors of said trunk line, and automatic means effective only when a connection is extended over said trunk line from a particular point for increasing the impedance of said bridge.
- 100 21. In a telephone system, a trunk line consisting of talking conductors accessible from two different points, means for extending a connection from either point over said trunk line to a called telephone line, a battery supply bridge connected across the talking conductors of said trunk line, and automatic means effective only when a connection is extended over said trunk line from a particular point for decreasing the impedance of said bridge.
- 105 22. In a telephone system, a trunk line consisting of talking conductors accessible from two different points, means for extending a connection from either point over said trunk line to a called telephone line, a battery supply bridge connected across the talking conductors of said trunk line, and automatic means effective only when a connection is extended over said trunk line from a particular point for increasing the resistance of said bridge.
- 110 23. In a telephone system, a trunk line consisting of talking conductors accessible from two different points, means for extending a connection from either point over said trunk line to a called telephone line, a battery supply bridge connected across the talking conductors of said trunk line, and automatic means effective only when a connection is extended over said trunk line from a particular point for decreasing the resistance of said bridge.
- 115 24. In a telephone system, a trunk line consisting of talking conductors accessible from two different points, means for extending a connection from either point over said trunk line to a called telephone line, a battery supply bridge connected across the talking conductors of said trunk line, and automatic means effective only when a connection is extended over said trunk line from a particular point for increasing the impedance of said bridge.
- 120 25. In a telephone system, a trunk line consisting of talking conductors accessible from two different points, means for extending a connection from either point over said trunk line to a called telephone line, a battery supply bridge connected across the talking conductors of said trunk line, and automatic means effective only when a connection is extended over said trunk line from a particular point for decreasing the impedance of said bridge.
- 125 26. In a telephone system, a trunk line consisting of talking conductors accessible from two different points, means for extending a connection from either point over said trunk line to a called telephone line, a battery supply bridge connected across the talking conductors of said trunk line, and automatic means effective only when a connection is extended over said trunk line from a particular point for increasing the resistance of said bridge.
- 130 27. In a telephone system, a trunk line consisting of talking conductors accessible from two different points, means for extending a connection from either point over said trunk line to a called telephone line, a battery supply bridge connected across the talking conductors of said trunk line, and automatic means effective only when a connection is extended over said trunk line from a particular point for decreasing the resistance of said bridge.

- including a repeater, means for setting up a circuit connection over said trunk line from two different points for talking purposes, a controlling relay bridge across said circuit 5 in said repeater, an impedance coil for insertion in the bridge, and a marginal relay in said repeater effective to cause the inclusion of said coil in the said relay bridge only when a connection is extended over 10 said trunk line from a particular point.
18. In a telephone system, first and second subscribers' lines, means including a switching mechanism controllable over either of said lines when calling for extending a 15 talking connection to a called line, a battery supply bridge in said mechanism, and a marginal relay for increasing the impedance of said bridge if a particular one of said first lines is included in the connection.
19. In a telephone system, first and second subscribers' lines, means including an electromagnetic switching mechanism controllable over either of said lines when calling for extending a talking connection to a 20 called line, a battery supply bridge in said mechanism, means for supplying talking current by way of said bridge to the said 25 first line after the connection is completed, and a marginal relay for automatically increasing the resistance and impedance of 30 said bridge if the said second line is the calling line.
20. In a telephone system, first and second subscribers' lines, means including an electromagnetic switching mechanism controllable over either of said lines when calling for extending a talking connection to a called line, a battery supply bridge in said mechanism, and a marginal relay for 35 changing the resistance of said bridge if a 40 particular one of said first lines is included in the connection.
21. In a telephone system, selector switches of two different kinds, a repeater accessible to said switches, means including either one 45 of said switches and said repeater for connecting calling and called lines, a battery supply bridge in said repeater, and a marginal relay for increasing the impedance of 50 said bridge if the established connection includes a selector switch of a particular kind.

Signed by me at Chicago, Cook county,
State of Illinois, this 24th day of May, 1917.
TALBOT G. MARTIN.
